UNITED STATES PATENT OFFICE.

THOMAS V. PLICE, OF ASHLAND, OHIO, ASSIGNOR TO W. V. B. TOPPING, OF ASHLAND, OHIO.

DOOR STRUCTURE.

1,191,223.

Specification of Letters Patent. Patented July 18, 1916.

Application filed October 25, 1915. Serial No. 57,700.

To all whom it may concern:

Be it known that I, THOMAS V. PLICE, a citizen of the United States, resident of Ashland, county of Ashland, and State of Ohio, have invented a new and useful Improvement in Door Structures, of which the following is a specification, the principle of the invention being herein explained and the best mode in which I have contemplated applying that principle, so as to distinguish it from other inventions.

My invention relates to door-structures, its object being to provide a structure which is economical of manufacture, efficient in the performance of its function and which, when open, will require a minimum of space for its accommodation.

The door embodying my invention is particularly adapted for use in garages.

My said invention consists of means hereinafter fully described and particularly set forth in the claims.

The annexed drawings and the following description set forth in detail certain means embodying my invention, the disclosed means, however, constituting but one of various mechanical forms in which the principle of the invention may be applied.

In said annexed drawings: Figure 1 represents a front elevation of a door-structure embodying my invention and showing a fragmentary portion of the front of the garage. Fig. 2 represents, upon an enlarged scale, a front view of a fragmentary portion of the door showing the locking means attached thereto. Fig. 3 represents a vertical section of the parts shown in Fig. 2 and taken upon the plane indicated by line III—III in Fig. 2. Fig. 4 represents a horizontal section of the garage taken upon the plane indicated by line IV—IV, in Fig. 1, showing the door in its closed position. Fig. 5 represents a view similar to that of Fig. 4 and showing the door in two partially opened positions, one of which is shown in dotted lines. Fig. 6 represents a view similar to those of Figs. 4 and 5 and showing the door in its fully opened position. Fig. 7 represents a front elevation of a fragmentary portion of the garage, upon an enlarged scale, together with the door-hanger forming part of my invention. Fig. 8 represents a vertical section of the parts shown in Fig. 7 and taken upon the plane

indicated by line VIII—VIII in said figure.

The illustrated embodiment of my invention comprises a door consisting of two parts, or leaves 1, 1, of such size as to properly fill the door opening 2, formed in the front wall 3, of the garage. These two parts are as shown divided in a vertical plane and are connected to each other by means of hinges 4, 4, which are secured upon the inner surfaces respectively, of the two parts so that the latter may swing so as to bring their inner faces adjacent to each other, as shown in Fig. 6. The one part 1 is secured at one edge portion or jamb by means of hinges 5, 5, to the garage wall 3 which forms the support for the door structure. These hinges are so placed that this part 1 may swing outwardly, as shown in Fig. 5. Above the door opening and in a horizontal plane coincident with or parallel with the lintel, is a trolley track 6 secured to the outer ends of brackets 7, 7, which themselves are secured in a suitable manner to the front wall 3, as shown in Figs. 4 and 5. This track is also parallel with the front wall 3 throughout the major portion of the width of the door opening, but curves outwardly and away from the wall at that portion, 6, thereof which is adjacent to the axis of oscillation 85 formed by the hinges 5, the curve beginning at a point on one side of such axis and ending substantially opposite the latter, as shown. As shown in the drawings this track is also provided with a terminal portion 6^b which is removed a distance from the wall of the structure equal to the distance which the outermost portion of the curved part of the track is removed, as clearly shown in Figs. 4 and 5. This distance must be at least equal to the sum of the two door thicknesses plus the extent of outward projection of the roller carrying bracket.

The function of the curve in the track 100 is to facilitate the door closing operation by bringing the two parts together gradually. In some degree, the effect of this curve is exerted upon the outer flange of the roller 10. The curve of the track may be said to push the roller and therefore the hanger and the free door edge into that course with reference to the hinges 5 by which the ap-

proach of the two door parts will be made gradual and easy. The shape of the track also controls the position of the two parts of the door after the folding is practically complete, that is, the flat open position of Fig. 6.

Secured upon the outer face of the other part 1 of the door and at the upper right hand corner thereof, is a door-hanger member 8 which is provided with a bore 9 having a vertical axis, in which bore are seated rollers 10. These rollers form a bearing for cylindrical stem 11 forming the lower part of a trolley-frame 12, in which is suitably mounted a trolley-wheel 13. This wheel runs upon the track 6, as shown. The lower end of the stem 11 projects beyond the member 8, is threaded and has mounted upon said threaded portion a nut 14 provided with a slot 15 through which passes a cotter-pin 16. Between the nut and the member 8 is placed a washer 17. The position of the parts are such that the nut 14 will sustain the swinging end of the door, as will be understood.

A locking device is provided for securing the two door-parts to each other when the door is in its closed position, that is, when the two door-parts are in alinement, as shown in Figs. 1 and 4. This locking device consists preferably of a hasp 18 pivoted upon a bolt 19 secured to one of the door-parts, and a staple 20 secured to the other of the two door-parts and passing through a slot 21 formed in the hasp. A strap 22 holds the hasp in place when it is not engaging the staple. The latter is formed with a shoulder 23, Fig. 3, and with an inclined surface 24 so that when the two parts are swung into their closed position, the hasp will automatically engage the staple, as will be readily understood. This hasp is also provided at its free end with a loop 25 adapted to permit it to be readily grasped by the hand.

Assuming the door to be in its closed position, that is, in the position in which the two door parts are in alinement, when it is desired to open the door, the hasp is lifted upwardly so as to disengage the staple. By then pulling outwardly upon the hasp, the door swings upon the hinges 5, the trolley-wheel travels toward the hinged end of the door, and the two parts of the latter assume an annular position with reference to each other, as shown in Fig. 5. Further pulling upon the hasp, or if desired, pushing upon the right hand door-part 1, will bring the

two parts in the position shown in dotted lines in Fig. 5 in which the trolley-wheel is 60 just beginning to traverse the curved portion of the track. In this position it will be noted that the two door-parts are folded upon each other. Further pushing upon the door will bring it into the position shown 65 in Fig. 6 in which it is substantially parallel with the wall 3 of the building, with the trolley riding upon the part 6^b of the track as shown in Fig. 6. It will be noted that in this position, the open door occupies only 70 half the space laterally of the hinges 5 as is occupied by an ordinary door which would be required to close a similar opening.

To close the door, the above described operation is reversed. 75

Having fully described my invention, what I claim and desire to secure by Letters Patent is:—

1. In a door structure, the combination of a suitable support; a two-part door, one 80 part of which is hinged to such support and the other part of which is hinged to said first-named part; a hanger, a track fixed with relation to said support and parallel with the latter throughout its major portion, the end portion being spaced from the wall a distance equal to the sum of the two door thicknesses plus the extent of outward projection of the hanger, and curved inwardly to connect with said major portion 90 on a radius substantially equal to the distance of said end portion from the wall and about a center in line with the axis of the hinged section, but in the plane of the track; and said hanger secured to said second-named door part, movable upon said track. 95

2. In a door structure, the combination of a suitable support; a two-part door, one part of which is hinged to such support and the other part of which is hinged to said first-named part; a track fixed with relation to said support; and a member secured to said second-named door part, movable upon said track; said track for the greater part of its length being parallel to the closed position 105 of the door but being curved outwardly from the support toward the rear, said curved portion of the track being limited both in its length and in its projection transversely to the main portion to the extent 110 necessary to allow the door to assume its doubled and folded back position.

Signed by me, this 24th day of September, 1915.

THOMAS V. PLICE.
